UNITED STATES PATENT OFFICE.

HAROLD A. WIBERG, OF NEW YORK, N. Y.

RECORD CABINET.

Application filed May 31, 1922. Serial No. 564,953.

To all whom it may concern:

Be it known that I, HAROLD A. WIBERG, a citizen of Sweden, residing at New York city, in the county of New York and State of New York, have invented certain new and useful Improvements in Record Cabinets, of which the following is a specification, reference being had to the accompanying drawings.

10 It is a purpose of the present invention to provide a record cabinet, wherein improved features of construction are involved, and also wherein the construction of the record suspension means involves improvements 15 upon the corresponding means in the Patent No. 1,351,596, issued to Harold A. Wiberg, August 31, 1920.

Another purpose is to provide an improved record suspension means and portable cabinet therefor, so that records may be supported in perpendicular positions, that is to say, in parallel relation, so that the records may be easily carried from one place to another, due to the portability of the 25 cabinet.

Still another purpose is the provision of a cabinet, including a plurality of cord suspension means for records, in fact the holder or hammock for the record, in combination 30 with means for holding the cord holder or hammock at the rear, in the proper positions in order to prevent the records from excessively moving toward and contacting with each other.

35 A further purpose is the provision of record cord holders or hammocks, certain of which, say for instance every other holder or hammock includes means constituting part of the cord hammock or holder, for holding the same steady, and to prevent certain of the records from becoming entangled with certain of the holders, and a still further purpose is to arrange certain of the cord record holders or hammocks unattached to 40 the frame, in order to suspend certain of the records free so that when removing a record, it may be easily and very readily grasped.

Still further, the invention aims to provide a cabinet including a frame, on which 50 the record cord holders or hammocks are suspended, in combination with a suitable hood, to fit downwardly over the frame, there being an opening in the top of the hood to permit the handle of the frame to 55 pass therethrough, in order that the handle

may be grasped for permitting the cabinet to be moved from one place to another.

It is to be understood that the particulars herein given are in no way limitative and that while still keeping within the scope of 60 the invention, any desired modifications of detail and desired proportions may be made in the apparatus according to circumstances.

The invention comprises further features and combination of parts, as will be herein- 65 after set forth, shown in the drawings and claimed.

In the drawings:—

Figure 1 is a view in perspective of the improved record cabinet, showing the casing 70 or hood in position, whereby the cabinet may be carried from one place to another;

Figure 2 is a vertical sectional view on line 2—2 of Figure 1, showing the frame together with the record suspension means, 75 and illustrating the handle carried by the frame and passing through the hood or casing;

Figure 3 is a vertical sectional view at right angles to Figure 2 on line 3—3 there- 80 of, thereby not only showing the frame but also the various numbers belonging to the records;

Figure 4 is a plan view of the frame, showing the numbers on the top; 85

Figure 5 is an enlarged detail view of the frame removed;

Figure 6 is a detail perspective view of one of the cord record suspension means or hammocks; 90

Figure 7 is a view of another record cord holder or suspension means.

Referring to the drawings, 1 designates a suitable frame, for the support of a plurality of talking machine records. This frame comprises a base having a marginal flange 2, and rising from the flange at points directly opposite each other are upright studs 4, the upper ends of which are connected by a cross piece 5.

The front and rear portions of the marginal flange have their inner surfaces 7 inclined inwardly and downwardly toward the bottom of the base of the frame, thereby preventing the records, when detached from the hammocks or record suspension means, from rolling off or out of contact with the ground.

The inner or adjacent faces of the upright studs are provided with felt cushions 8, 110

which prevent the records from contacting with the studs, and thereby avoid scratching or otherwise injuring the records.

The cross piece 5 of the frame adjacent its rear face, and extending from the upper edge of the cross piece, is provided with a plurality of cuts or notches 9. Furthermore the cross piece 5 has a longitudinal depression or groove 10. Projecting upwardly from the cross piece and secured thereto in any suitable manner, is a looped handle 11, which passes through a slot 12 in a hood 13, which fits over the frame, until the lower marginal edge (which is provided with felt) of the hood, contacts with the base or table top or any other suitable support, when the records are covered. In fact the lower marginal edge of the wall of the hood assumes a position even or flush with the under surface of the bottom of the frame. A suitable lock, latch or any other fastening means (not shown) may be carried by the base or bottom of the frame, to co-operate with the hood, for connecting the hood to the base, whereby the cabinet may be portable from one place to another.

In order to suspend the records on the frame, which is covered by the cabinet, a plurality of cord record holders, hammocks 30 or suspension means 16 is provided. These suspension means for the records are suspended from the cross piece 5, as shown in the drawings clearly. One end of each hammock or record suspension means is provided with a knot 17, which assumes a position in the slot or groove 10 of the cross piece, while the end portion of the suspension means or holder engages any one of the notches of the rear portion of the cross piece.

The front face of the cross piece is provided with upper and lower rows of hooks 18 and 19, the hooks of the upper row correspond to and are opposite certain of the notches of the rear of said cross piece, while the lower row of hooks correspond to and are below certain other of said notches. The hooks receive the other ends of the cord record holders or suspension means, for the purpose of holding the records suspended upon the frame, and slightly out of contact with the felt covered upper base of the bottom of the frame. This felt covered base at the bottom of the frame prevents injury to the records, when they are released and allowed to contact with the base.

Certain of the suspension means have their lower portions (which are constructed of cord) in the form of a carrier or hammock, which receives a record in a perpendicular position, as shown in Figures 2 and 6. Certain of the cords designated by the characters 21, 22 and 23 engage the edge of the record, and are located upon opposite sides of the record. Cords 24 of certain of the suspension means extend from the notches

of the cross piece 5 downwardly and inclined, and have their lower ends attached at 25 to the rear portion of the flange of the base, so as to steady and hold the suspension means in position. Cords 26 of certain of the suspension means are connected at 27 to the lower portion of the suspension means, and are in turn connected at 28 to the cords 24. In fact the strands 26 are in one piece, the loop 29 of which engages the rear upper portion of the edge of the record. By this construction of hammock or suspension means, the records are prevented from becoming entangled with the adjacent suspension means, when the record is being inserted.

Certain other suspension means simply consist of the cords 30 and 31 and the downwardly and rearwardly and forwardly extending cords 32 and 33. The cords 32 of this suspension means are attached in the notches, the same as the other cord suspension means. The strands or cords 33 have metal loops 34, which connect with the upper hooks 18, while the corresponding cords 30 or strands of the other suspension means have their loops engaging the lower hooks 19.

The notches are numbered one to twenty-four, the odd numbers are located upon the upper edge of the cross piece 5 while the even numbers are located upon the front face of the cross piece 5. A suitable book or pamphlet (not shown) with its pages alphabetically designated is adapted to be used in connection with the present form of cabinet. In other words the titles of the records and by whom rendered are written in the book or pamphlet in their alphabetical order, and each record is given a number, indicated in the book. Obviously should it be desired to play a certain record, the title is first found in the pamphlet (not shown), and then a notation is made of the number of this record. The cabinet is then lifted from the frame, then the number, according to the title of the record may be removed from its hammock, or removed from the cabinet. In order to restore a record, the record is placed between the opposite parts of the suspension means, and then the loop 34 thereof is connected to its respective hook on the cross piece.

Obviously, the term "suspension means" conveys the fact that they are of such construction as to hold or support the lower edges of the records out of contact with the bottom of the cabinet. In other words if the suspension means were not adapted to support the lower edges of the records out of contact with the bottom of the cabinet, then such supporting means could not be so termed. Furthermore the cords used in the construction of the suspension means, in practice, are relatively thick, therefore act as cushions between the records, while in

their suspended positions, thereby preventing the records from contacting and becoming scratched or otherwise injured.

As previously stated the handle of the frame projects through the hood, and may be easily grasped, in order to permit the cabinet to be moved from one place to another.

The rear edge of the base of the frame is provided with an insert strip of fabric 25^a, to which the cords 24 are attached. In fact the cord 24 has its loop at its lower portion engaged through the strip of fabric.

Stretched across the rear end of the base of the frame is an elastic or non-elastic band or similar strip 25^a under which the cord hammocks may be passed, and then connected to the hooks 19, when the hammocks are not in use.

The invention having been set forth, what is claimed is:—

1. In a record cabinet, a frame, a plurality of suspension means each being engaged with the bottom edge of the record and having one of its ends attached to the upper portion of the frame, and its other end detachably connected to the upper end of the frame whereby upon detaching the latter end, a record may be removed.

2. In a record cabinet, a frame, a plurality of suspension means each having one of its ends attached to the upper portion of the frame, and its other end detachably connected to the upper end of the frame, whereby upon detaching the latter end, a record may be removed, said suspension means comprising a hammock portion at its lower part, for the reception and the support of a record.

3. In a record cabinet, a frame, a plurality of suspension means each having one of its ends attached to the upper portion of the frame, and its other end detachably connected to the upper end of the frame, whereby upon detaching the latter end, a record may be removed, and means constituting a part of the suspension means and extending from the upper portion of the frame downwardly to the rear of the frame and connected thereto, to steady and hold the suspension means in position.

4. In a record cabinet, a frame, a plurality of suspension means each having one of its ends attached to the upper portion of the frame, and its other end detachably connected to the upper end of the frame, whereby upon detaching the latter end, a record may be removed, said suspension means comprising a hammock portion at its lower part, for the reception and the support of a record, and means constituting a part of the suspension means and extending from the upper portion of the frame downwardly to the rear of the frame and connected thereto, to steady and hold the suspension means in position.

5. In a record cabinet, a frame, a plurality of suspension means each having one of its ends attached to the upper portion of the frame, and its other end detachably connected to the upper end of the frame, whereby upon detaching the latter end, a record may be removed, said suspension means comprising a hammock portion at its lower part, for the reception and the support of a record and means constituting a part of the suspension means and extending from the upper portion of the frame downwardly to the rear of the frame and connected thereto, to steady and hold the suspension means in position, and means connected to the center portions of the opposite sides of the hammock portion and adapted to engage the upper rear edge of a record, to steady and hold the record in position.

6. In a record cabinet, a frame including means for suspending a plurality of records from its upper portion, a handle carried by the upper central portion of the frame, and a hood to fit down over the frame and provided at its top portion with a centrally disposed slot, through which the handle passes, whereby the handle may be grasped, and the cabinet be portable from one place to another, said hood extending down and engaging the edge of the base of the frame to entirely enclose the records.

7. In a record cabinet, a frame including a removable cover, cord suspension means connected to the rear face of the upper portion of said frame, each of said cord suspension means engaging the bottom edge of a record, and having its other end detachably connected to the front part of the upper portion of said frame, and cushions upon opposite sides of said frame, to prevent the record from contacting with the frame.

8. In a record cabinet, a frame including a removable cover, cord suspension means connected to the rear face of the upper portion of said frame, each of said cord suspension means adapted to support a record, and having its other end detachably connected to the front part of the upper portion of said frame, and cushions upon opposite sides of said frame, to prevent the record from contacting with the frame, the cord suspension means acting as cushions between the records, to prevent the records from scarring or otherwise becoming injured.

9. In a record cabinet, a frame, a plurality of suspension means, each engaging the greater portion of the bottom of the edge of a record and provided with means at its upper portion for detachable connection with the upper part of the frame, thereby supporting the record swingingly in position.

10. In a record cabinet, a frame, a plurality of suspension means, each engaging the greater portion of the bottom of the edge of a record and provided with means at its

upper portion for detachable connection with the upper part of the frame, thereby supporting the record swingingly in position, and a cushion extending across one edge of the ends of the frame immediately adjacent the edges of the records to perform the double-fold purpose of cushioning the edges of the records and to permit the suspension means to engage therewith when not in use.

11. In a record cabinet, a frame, a plurality of suspension means detachably suspended from the top of the frame and provided with a hammock construction for engaging the bottom edges of the records for supporting them swingingly in position. 15

In testimony whereof I hereunto affix my signature.

HAROLD A. WIBERG.
